UNITED STATES PATENT OFFICE.

JOHN V. STEWART AND FRANK G. WERTZ, OF JOHNSTOWN, PENNSYLVANIA.

TONGUE SWITCH.

Application filed December 18, 1923. Serial No. 681,339.

To all whom it may concern:

Be it known that we, JOHN V. STEWART and FRANK G. WERTZ, citizens of the United States, and residents of Johnstown, in the county of Cambria and State of Pennsylvania, have invented certain new and useful Improvements in Tongue Switches, of which the following is a specification.

This invention relates to tongue switches and more particularly to means for operating and locking the tongues in thrown position.

One object of this invention is to provide means whereby the switch tongue may be swung to either side of the body and locked in position in a single operation.

Another object is to provide a tongue switch having the novel operating and locking means described in the following specification and illustrated in the accompanying drawings.

In the drawings,

Figures 1 and 1^a combine to form a top plan of a switch structure embodying this invention.

Figures 2 and 2^a combine to form a sectional side elevation thereof.

Figure 3 is a transverse sectional elevation on the line III—III of Figure 1.

30 Figure 4 is a transverse sectional elevation on the line IV—IV of Figure 1^a.

Referring more particularly to the drawings, the numeral 2 designates the body portion of the tongue switch as a whole, which 35 is of the ordinary well known construction, and is provided with a groove or depression 3 in its floor, in which is mounted the usual tongue 4 having a downwardly projecting lug 5 to which the tongue operating rod 6 is 40 secured.

A box 7 for containing the switch operating mechanism is secured to the side of the switch body 2 by bolts 8.

The tongue operating rod 6 extends 45 through a suitable aperture in the body 2 and into the box 7, and is pivotally secured in an eccentric bearing member 9 adjustably mounted in an arm 10 of a substantially universal mounting A. The universal 50 mounting A is composed of a vertical pin or shaft 11 mounted for horizontal pivotal movement in the box 7, and having the horizontally disposed integral arm 10 and a bail or U-shaped link member 12 pivotally 55 mounted thereon for vertical swinging movement.

An operating hand lever 14 is pivotally mounted on a horizontally disposed pivot pin 15 secured to the side of the box. The lever 14 is offset as at 16 adjacent the pivoted end and is provided at the offset portion with an aperture to receive a pivot lug 17 on the bail or U-shaped link 12.

The operation of the tongue operating mechanism above described is as follows— 65 Assuming that the mechanism is in the position shown, the hand lever 14 will be raised, and due to the universal mounting A, considerable lost motion is had, since the first operation or lifting movement of the lever 70 14 will raise the bail or U-shaped link 12 an appreciable amount before the mounting A is moved about the pivot pin 11. After the link 12 has been raised a sufficient distance, the link will act as a lever to rotate 75 the pivot pin 11 about its vertical axis, thus moving the lever or arm 10 rearwardly and operating the rod 6 to swing the switch tongue.

A locking or latch mechanism is provided 80 for locking the tongue in its thrown or swung position at both sides of the body 2 and comprises a locking bar 20 mounted for a reciprocating or sliding movement in a guide and supporting structure 21 formed 85 integral with the switch body 2 below the floor thereof. The bar 20 is provided at its forward or free end with a head 22 adapted to engage the side face of the lug 5 on the tongue. The rear end of the bar 20 has a ball and socket connection 23 with one arm of a bell crank lever 24 which lever is in turn pivotally mounted on a pin 25 secured in the switch body 2. The other arm of the lever 24 is pivotally connected to one 90 end of a link 26 which has its other end pivotally connected to a link coupling member 27. The coupling member 27 is connected to a lock operating rod 28 which is in turn connected at 29 to a manipulating bar 30. 100

The manipulating bar 30 is pivotally connected at each end to one arm of L-shaped or bell crank operating levers 31, which levers are in turn pivotally connected at the junction of their arms to ears 32 formed integral with the bottom of the box 7. The other arm of each of the levers 31 has its free end enlarged and provided with an open slot 33 to receive a connecting pin 34 carried by the hand lever 14.

In operation, assuming that the parts are in the position shown in the drawings, the

first upward movement of the hand lever 14, that is the lost motion movement, will lift or rock the left hand lever 31 about its pivot, and thus reciprocate the bar 30 and rock the second lever 31 and reciprocate the rod 28 and link 26. The reciprocating of the rod 28 and link 26 will rock the bell crank lever 24 and thus withdraw the locking bar 20 so as to disengage its head 22 from the lug 5. The hand lever 14 is adapted to move the bell crank 31 until it reaches the limit of its lost motion, and the parts are so proportioned and adjusted that the locking bar 20 will be free of the lug 5 when the hand lever 14 reaches this position. As the hand lever reaches the end of its lost motion movement, the pin 34 will move out of the open slot 33 and further movement of the lever 14 will operate the rod 6 to move the tongue 4 from one side to the other of the switch body 2. After the lever 14 has been moved past center and has completed the movement of the switch tongue, it will again be subjected to lost motion in lowering the U-shaped link 12, and as this movement starts, the pin 34 on the lever 14 will enter the open slot 33 in the right hand bell crank lever 31 and cause the levers 31 and bar 30 to move to the left or in a reverse direction, thus again forcing the locking bar 20 inwardly so that its head 22 will engage the right hand side of the lug 5 and lock the tongue 4 in its new position.

It will, of course, be understood that when the lever 14 is moved to the left the parts will operate in the reverse direction and return to the position shown in the drawings.

In order to prevent the manipulating bar 30 and bell crank levers 31 moving beyond the release position, at which time the one lever 31 is in position to release the pin 34 and the other lever 31 is in position to receive the pin 34, a flexible stop is provided. This stop comprises a roller 38 mounted in a lever 39 having one end pivoted at 40 to a suitable lug on the bottom of the box 7 and having its other end supported by a coiled spring 41. The roller 38 is adapted to enter a depression 42 in the lower face of the bar 30 and so flexibly hold the bar 30 and levers 31 in position until unseated by the positive action of the lever 14 as the pin 34 enters the slot in the other lever 31.

It will be noted the tongue operating rod 6 is shown continued through the right hand side of the switch body 2 and that a rod 45 is shown extending from the link coupling through the switch body 2 to the right hand side thereof. The continuation of the tongue operating rod 6 and the rod 45 are shown to illustrate the manner in which double rail tongue switches may be operated by the single hand lever and lock operating means. If double rail tongue switches are to be operated the second

tongue switch would be a duplicate of that shown in the drawings, and the continuation of rod 6 would be secured to the lug 5 while the rod 45 would be connected to the bell crank lever 24 of the second tongue locking mechanism.

It will be understood, however, that when only one tongue switch is being used the rod 6 will be terminated at the lug 5 and the rod 45 will be omitted.

While we have shown and described only one specific embodiment of our invention it will be expressly understood that we do not wish to be limited thereto, since various modifications may be made without departing from the scope of the appended claims.

We claim:

1. The combination with a tongue switch comprising a suitable body portion and a tongue adapted to be swung from side to side thereof, said tongue being provided with a downwardly projecting lug on its bottom face, of a tongue operating rod connected to said lug, a pivoted tongue operating lever connected to said rod and adapted to reciprocate said rod to swing said tongue, means for permitting lost motion between said operating lever and said tongue operating rod, and other means operated by said lever during the lost motion movement adapted to lock said tongue in position, said means comprising a locking bolt mounted for reciprocatory movement in said switch body and being provided at its free end with a head portion adapted to engage the side face of said downwardly projecting lug on said tongue, said bolt, having its rear end connected by a ball and socket connection with one arm of a horizontally movable bell crank lever pivotally mounted in said switch body, the other end of said bell crank lever being connected by suitable links to a horizontally movable manipulating bar, said bar having each end pivotally connected to one arm of a bell crank lever, said last named bell crank levers having their free arms provided with open slots, and a connecting pin projecting from the side of said tongue operating rod adapted to engage in said open slots in said bell cranks during the lost motion movement of said rod, thereby operating said bell cranks, manipulating bar and connected mechanism to cause the operation of said locking bolt prior to the movement of said switch tongue.

2. The combination with a tongue switch comprising a suitable body portion and a tongue adapted to be swung from side to side thereof, said tongue being provided with a downwardly projecting lug on its bottom face, of a tongue operating rod connected to said lug, a pivoted tongue operating lever connected to said rod and adapted to reciprocate said rod to swing said tongue, means for permitting lost motion between

- said operating lever and said tongue operating rod, and other means operated by said lever during the lost motion movement adapted to lock said tongue in position, 5 said means comprising a locking bolt mounted for reciprocatory movement in said switch body and being provided at its free end with a head portion adapted to engage the side face of said downwardly projecting 10 lug on said tongue, said bolt having its rear end pivotally connected to one arm of a horizontally movable bell crank lever, the other arm of said bell crank lever being connected by a suitable link mechanism to a horizontally 15 movable manipulating bar, means adapted to connect said manipulating bar and said switch tongue operating lever during the lost motion movement of said lever to cause a reciprocatory movement of said manipulating bar and operation of its associated mechanism to thereby operate said locking bolt prior to the operation of said switch tongue, and a flexible stop for limiting the movement of said manipulating bar. 15
3. The combination with a tongue switch 20 comprising a suitable body portion and a tongue adapted to be swung from side to side thereof, said tongue being provided with a downwardly projecting lug on its bottom face, of a tongue operating rod connected to said lug, a pivoted tongue operating lever connected to said rod and adapted to reciprocate said rod to swing said tongue, means for permitting lost motion between said operating lever and said tongue operating 25 rod, and other means operated by said lever during the lost motion movement adapted to lock said tongue in position, said means comprising a locking bolt mounted for reciprocatory movement in said switch 30 body and being provided at its free end
- with a head portion adapted to engage the side face of said downwardly projecting lug on said tongue, said bolt having its rear end pivotally connected to one arm of a horizontally 35 movable bell crank lever, the other arm of said bell crank lever being connected by a suitable link mechanism to a horizontally movable manipulating bar, means adapted to connect said manipulating bar and said switch tongue operating lever during the lost motion movement of said lever to cause a reciprocatory movement of said manipulating bar and operation of its associated mechanism to thereby operate said locking bolt prior to the operation of said switch tongue, and a flexible stop for limiting the movement of said manipulating bar. 4. The combination with a tongue switch 40 comprising a suitable body portion and a tongue adapted to be swung from side to side thereof, said tongue being provided with a downwardly projecting lug on its bottom face, of a locking bolt mounted for reciprocatory movement in said switch body and being provided at its free end with a head portion adapted to engage the side face of said downwardly projecting lug on said tongue, said bolt having its rear end pivotally connected to one arm of a horizontally 45 movable bell crank lever, the other arm of said bell crank lever being connected by a suitable link mechanism to a horizontally movable manipulating bar, means adapted to connect said manipulating bar and said switch tongue operating lever during the lost motion movement of said lever to cause a reciprocatory movement of said manipulating bar and operation of its associated mechanism to thereby operate said locking bolt prior to the operation of said switch tongue, and a flexible stop for limiting the movement of said manipulating bar. 45
4. The combination with a tongue switch 50 comprising a suitable body portion and a tongue adapted to be swung from side to side thereof, said tongue being provided with a downwardly projecting lug on its bottom face, of a locking bolt mounted for reciprocatory movement in said switch body and being provided at its free end with a head portion adapted to engage the side face of said downwardly projecting lug on said tongue, said bolt having its rear end pivotally connected to one arm of a horizontally 55 movable bell crank lever, the other arm of said bell crank lever being connected by a suitable link mechanism to a horizontally movable manipulating bar, means adapted to connect said manipulating bar and said switch tongue operating lever during the lost motion movement of said lever to cause a reciprocatory movement of said manipulating bar and operation of its associated mechanism to thereby operate said locking bolt prior to the operation of said switch tongue, and a flexible stop for limiting the movement of said manipulating bar. 55

In testimony whereof we have hereunto set our hands.

JOHN V. STEWART.
FRANK G. WERTZ.
